CLAIM

We claim the ornamental design for a toothbrush handle, as shown and described.

DESCRIPTION

FIG. 1 is a front isometric view of a toothbrush handle with a toothbrush head shown for environment.

FIG. 2 is a front isometric view of the toothbrush handle of FIG. 1.

FIG. 3 is a front elevation view of the toothbrush handle of FIG. 2.

FIG. 4 is a rear elevation view of the toothbrush handle of FIG. 2.

FIG. 5 is a left side elevation view of the toothbrush handle of FIG. 2.

FIG. 6 is a right side elevation view of the toothbrush handle of FIG. 2.

FIG. 7 is a top plan view of the toothbrush handle of FIG. 2; and,

FIG. 8 is a bottom plan view of the toothbrush handle of FIG. 2.

The broken lines in the toothbrush handle of FIGS. 1-8 indicate features of the toothbrush handle that form no part of the claimed design. Additional broken lines shown in FIG. 1 are for purposes of illustrating environment only and form no part of the claimed design.
